(57) **CLAIM**

The ornamental design for an air disinfection and sanitization device as shown and described.

DESCRIPTION

FIG. 1 is a first perspective view of a air disinfection and sanitization device showing our new design;

FIG. 2 is a second perspective view thereof;

FIG. 3 is a top view thereof;

FIG. 4 is a bottom view thereof;

FIG. 5 is a right view thereof;

FIG. 6 is a left view thereof;

FIG. 6 is a top view thereof;

FIG. 7 is a front view thereof;

FIG. 8 is a rear view thereof;

FIG. 9 is a first perspective view of the air disinfection and sanitization device with the mount detached;

FIG. 10 is a second perspective view of the air disinfection and sanitization device with the mount detached;

FIG. 11 is a first perspective view of the air disinfection and sanitization device without the mount;

FIG. 12 is a second perspective view of the air disinfection and sanitization device without the mount;

FIG. 13 is a top view of the air disinfection and sanitization device without the mount;

FIG. 14 is a bottom view of the air disinfection and sanitization device without the mount;

FIG. 15 is a front view of the air disinfection and sanitization device without the mount;

FIG. 16 is a back view of the air disinfection and sanitization device without the mount;

FIG. 17 is a right view of the air disinfection and sanitization device without the mount;

(Continued)

FIG. 18 is a left view of the air disinfection and sanitization device without the mount;

FIG. 19 is a first perspective view of the mount;

FIG. 20 is a second perspective view of the mount;

FIG. 21 is a top view of the mount;

FIG. 22 is a bottom view of the mount;

FIG. 23 is a front view of the mount;

FIG. 24 is a back view of the mount;

FIG. 25 is a left view of the mount; and,

FIG. 26 is a right view of the mount.

The broken lines in the drawings depict portions of the air disinfection and sanitization device that form no part of the claimed design.
